Attorney

UNITED STATES PATENT OFFICE.

JAMES ALEXANDER COCHRANE, OF ROCHESTER, NEW YORK.

SASH-RETAINING DEVICE FOR WINDOWS.

1,129,550.

Specification of Letters Patent. Patented Feb. 23, 1915.

Application filed February 10, 1914. Serial No. 817,866.

To all whom it may concern:

Be it known that I, JAMES A. COCHRANE, a citizen of the United States, residing at Rochester, in the county of Monroe and 5 State of New York, have invented certain new and useful Improvements in Sash-Retaining Devices for Windows; and I do hereby declare the following to be a full, clear, and exact description of the invention, such as will enable others skilled in the art to which it appertains to make and use the same, reference being had to the accompanying drawings, and to the letters and figures of reference marked thereon, which 10 form a part of this specification.

This invention relates to new and useful improvements in means for holding sashes in window frames.

The invention comprises a simple and 20 efficient device of this nature having various details of construction, combinations and arrangements of parts which will be hereinafter fully described, shown in the accompanying drawings and then specifically 25 defined in the appended claim.

I illustrate my invention in the accompanying drawings, in which:

Figure 1 is a side elevation of a sash of 30 a window and frame showing the application of my invention, parts being illustrated in section, and Fig. 2 is a detail perspective view.

Reference now being had to the details of the drawings by letter, A designates the 35 frame of a window of the usual construction and B and C the sashes thereof. A removable sash-retaining strip K has a plate O fastened to the face thereof near its lower portion and the lower end of said plate projects beyond the end of the strip and is designed to engage a recess Q formed in the bottom of the sill. It will be noted that the strip K has a beveled portion at its lower end which engages a beveled wall of said 40 recess. The upper portion of the strip K is beveled as at R and engages the lower beveled end of a strip S. Secured to the face of the strip K, adjacent to its upper end, is a plate T with a raised portion T', 45 convexed upon its lower edge and adapted to be engaged by the bail-shaped member W which is pivotally mounted upon the casting J fixed to said strip S and which

member, when swung down to a locking position, is designed to engage the rounded 55 or convexed edge of the raised portion T' to securely hold the strip K in place.

A rope M has a retaining member I connected thereto and which latter is positioned in a recess I³ in the sash. The retaining member I is provided with an integral loop I' adapted to engage over a headed lug I² fastened to the wall of said recess. Said rope and attachment afford means whereby the rope may be conveniently detached from 60 the sash in the event of it being desired to remove the sash from the window. A plate having a downwardly extending hook K² is fastened to the sash A and is provided to receive the loop when detached from the 65 sash.

In operation, when it is desired to remove the sash, the bail-shaped member W is first 70 swung outwardly to release the same from the plate T, after which the upper end of 75 the strip K may be swung outward away from the frame and the strip K may then be raised so that the plate O will disengage the slot W. When the strip K is returned to its fixed position, the lower beveled end 80 thereof and the plate will engage the slot and beveled portion of the sill, as described, while the upper beveled end of the strip K will engage the lower end of the strip S, 85 after which the locking member may be swung down to position shown in Fig. 2 of the drawings.

What I claim to be new is:—

In combination with a window frame having a sill with a recess at one end thereof, 90 one wall of the recess being beveled and the other wall formed by the side of the frame, a sash retaining strip having its lower end beveled, a plate fastened to the face of said strip and projecting below the lower beveled end thereof and adapted to engage said recess, and means for holding the upper portion of said strip to the side of the frame. 95

In testimony whereof I hereunto affix my 100 signature in presence of two witnesses.

JAMES ALEXANDER COCHRANE.

Witnesses:

EMIL J. VILLNOW,
HARRY T. CLEMENT.
